UNITED STATES PATENT OFFICE.

WILLIAM E. GRAY, OF CHICAGO, ILLINOIS, ASSIGNOR TO MOORE ELECTRIC CORPORATION, OF CHICAGO, ILLINOIS.

HAIR CLIPPER.

Application filed July 14, 1921. Serial No. 484,795.

To all whom it may concern:

Be it known that I, WILLIAM E. GRAY, a citizen of the United States, and a resident of the city of Chicago, county of Cook, and 5 State of Illinois, have invented certain new and useful Improvements in Hair Clippers, of which the following is a specification.

My invention relates to improvements in hair clippers and more particularly the driving mechanism therefor, the object of the invention being to provide a simple and efficient driving mechanism for the clipper which will operate at suitable speed and substantially without vibration thereof.

15 Other objects will appear hereinafter.

The invention consists in the combinations and arrangements of parts hereinafter described and claimed.

The invention will be best understood by 20 reference to the accompanying drawings forming a part of this specification, and in which,

Fig. 1 is a bottom plan view shown partially in section and with parts removed of 25 a hair clipper embodying the invention,

Fig. 2 is a transverse vertical section thereof,

Fig. 3 is an enlarged section taken on line 3—3 of Fig. 2,

30 Fig. 4 is a top plan view of the cutting head of the clipper with the housing thereof removed, and

Fig. 5 is a section taken on line 5—5 of Fig. 3.

35 The preferred form of construction as illustrated in the drawings comprises the usual serrated cutter head 5 having the usual hollow handle 6 thereon. A driving shaft 7 is mounted in the handle 6 and provided at 40 its outer end with the usual socket 8 for the reception of and connection with the usual flexible shaft 9.

At its inner end the shaft 7 is provided with a crank 10 having comparatively little 45 eccentricity or "throw." The crank pin 10 is connected by a link 11 with a lever 12 at the point 13 intermediate the ends of said lever. At its upper end the lever 12 is fulcrumed at 14 and at its lower end said lever 50 is provided with a lug or finger 15 engaging a suitable notch or opening in a second lever 16. The lever 16 is fulcrumed at one end in the handle 6 and the other end thereof engages a notch 18 in the rear edge of a ser-

rated cutter blade 19 co-operating with the 55 head 5. A blade 19 is provided with slots 20 sliding on guide posts 21 on the head 5 and is held in place by means of a suitable housing 22 adjustably held in place by means of a set screw 23 and whereby the cutting 60 blade 19 will be held in operative relation with the cutting head 5 as will be readily understood.

The arrangement is such that the reciprocatory motion of the crank pin 10 is multiplied or made greater by the lever 12 and this motion is again multiplied or made greater by the lever 16, thus greatly multiplying the reciprocatory effect produced by said crank pin. In this way the crank pin 70 10 may be given but slight eccentricity or "throw" and will thus operate the cutting blade 19 with little or no vibration in the handle 6. In this way a smoothly operating and practically noiseless device is produced 75 by simple and easily understood and repaired parts and without the use of gearing.

While I have illustrated and described the preferred form of construction for carrying my invention into effect, this is capable of 80 variation and modification without departing from the spirit of the invention. I, therefore, do not wish to be limited to the precise details of the construction set forth, but desire to avail myself of such variations 85 and modifications as come within the scope of the appended claims.

Having described my invention, what I claim as new and desire to secure by Letters Patent, is:—

1. A hair clipper comprising a cutting head; a cutting blade reciprocating thereon; a hollow handle for said head arranged at an inclination to said blade; a driving shaft mounted in said handle at an inclination to 95 said blade; a crank on the inner end of said shaft having a comparatively small throw; a lever pivotally mounted in said handle and extending into said head and operatively connected with said blade; a second lever at 100 the inner end of said handle and swinging in a plane substantially at right angles to the axis of said shaft, the lower end of said lever being operatively connected with said first mentioned lever; and a link operatively connected with said crank and second mentioned lever, substantially as described.

2. A hair clipper comprising a cutting

head; a cutting blade reciprocating thereon; a hollow handle for said head; a driving shaft mounted in said handle with its inner end in operative relation with said blade; a 5 crank on the inner end of said shaft and having a comparatively small throw; a lever; a link operatively connecting said crank and said lever to multiply the motion of said crank; and a second lever operatively connected with said first lever and said cutting

blade to multiply the motion of said first lever, substantially as described.

In testimony whereof I have signed my name to this specification in the presence of two subscribing witnesses.

WILLIAM E. GRAY.
